(57) **CLAIM**

The ornamental design for a cookware vessel, as shown and described.

DESCRIPTION

FIG. 1 is a perspective view of a “cookware vessel”, showing my new design;

FIG. 2 is an elevational view thereof;

FIG. 3 is a top plan view thereof; and,

FIG. 4 is a bottom plan view thereof.

The cookware vessel of FIGS. 1-4 has a hammered texture applied over selected portions of the exterior.
